UNITED STATES PATENT OFFICE

FRANKLIN P. VAN HOOK, OF TOPEKA, KANSAS.

SILO.

1,095,481.

Specification of Letters Patent.

Patented May 5, 1914.

Application filed September 4, 1912, Serial No. 718,480. Renewed November 8, 1913. Serial No. 799,990.

To all whom it may concern:

Be it known that I, FRANKLIN P. VAN HOOK, a citizen of the United States, residing at Topeka, in the county of Shawnee 5 and State of Kansas, have invented certain new and useful Improvements in Silos, of which the following is a specification.

An object of the invention is to provide a silo.

10 The invention embodies among other features a structure adapted to contain ensilage in an airtight condition and which is constructed and arranged to permit of readily forcing the ensilage therein and removing the same therefrom.

15 The invention further embodies a structure which will present a neat and effective appearance and which is durably constructed to withstand great wear.

20 In the further disclosure of the invention reference is to be had to the accompanying drawings, constituting a part of this specification, in which similar characters of reference denote corresponding parts in all the 25 views, and in which;

Figure 1 is a side elevation of the silo, parts being broken away and disclosing the underlying structure thereof. Fig. 2 is an enlarged horizontal sectional view taken on 30 the line 2—2 of Fig. 1. Fig. 3 is a plan view of the silo, as shown in Fig. 1. Fig. 4 is an enlarged fragmentary vertical sectional view; showing the construction of the base and walls of the silo. Fig. 5 is a fragmentary perspective view of the skeleton frame. Fig. 6 is a perspective view of one of the closures for the silo, parts being broken away to disclose the underlying structure. Fig. 7 is a fragmentary perspective view of the sheathing employed in constructing the silo. Fig. 8 is a fragmentary perspective view of the cover or tank supporting members, showing the manner of mounting the same on the upper ends of the 40 uprights of the silo. Fig. 9 is a plan view of the follower, parts being broken away but disclosing the underlying structure. Fig. 10 is an enlarged fragmentary vertical sectional view taken on the line 10—10 in 45 Fig. 9.

50 Referring more particularly to the views I disclose a silo 10 including a base 11, preferably made of concrete, and a circular receptacle 12, the said receptacle being 55 adapted to receive the usual ensilage. The receptacle 12 consists more substantially of

a series of spaced studs 13, notched to receive reinforcing bands 13' embracing the same, the lower ends of the studs being sunk into the base 11 when the base is formed and connected by reinforcing wire 14, as shown in Fig. 5. The studs 13 are arranged in a circular manner, as disclosed in Fig. 2, and constitute a skeleton frame 15 of the silo 10. The receptacle 12 further includes 60 an inner wall 16 and an outer wall 17, the said inner and outer walls being spaced by the studs 13 to form air pockets 18 between the studs, as shown in Fig. 2. The inner and outer walls are somewhat similar in 65 construction and the inner wall is formed of an inner layer of plastering 19, a layer of reinforcing wire 20 arranged beneath the plastering, a layer of sheathing 21, such as is disclosed in Fig. 7, and a layer of plaster 70 22, the layer of plaster 22 being placed upon a face of the sheathing 21 and lying between the studs 13 of the skeleton frame 15, it being readily understood that the sheathing 21 is first secured to the studs 13, after 75 which the reinforcing wire is placed upon and stapled or otherwise secured to the inner face of the sheathing, the inner layer of plaster 19 being then placed upon the reinforcing wire to cover the same. The outer 80 wall 17 consists of sheathing 23 secured to the studs 13, after which a layer of reinforcing wire 25 is arranged to cover the sheathing, the whole being then covered by a layer of plaster 24 and which constitutes, 85 the outer surface of the silo 10, it being understood that the plaster that is employed in connection with the silo for the walls thereof is not of the ordinary kind but is of a particular grade and composition in 90 order that the plaster will thoroughly withstand the elements. At spaced distances uprights 26 are formed by pouring concrete or plaster between adjacent studs 13, reinforcing rods 27 being arranged to extend 100 longitudinally through the uprights 26 in order to strengthen the same, the mentioned uprights being adapted to extend the entire length of the silo, from the base to the upper end thereof, and also adapted to project beyond the upper surface of the silo 105 to receive pins 28 to which a rectangular frame 29 is connected, the said frame consisting of supporting bars 30 arranged as shown in Fig. 3 with rods 31 extending 110 diagonally from the pins 28 and connected by turnbuckles 32, thus permitting of tight

ening the rods in order to make the frame 29 rigid so that a suitable water tank or cover can be supported upon the uprights 26.

A chute 33 extends longitudinally from 5 the base to the upper end of the silo 10 to cover a series of closures 34 arranged in vertical alinement and which when removed will provide openings for gaining access to the interior of the receptacle 12, the 10 mentioned closures being individually arranged upon the receptacle in order that the ensilage therein can be conveniently removed therefrom, it being further seen that the mentioned closures each consist of space 15 walls 35 secured to a frame 36 and providing an intervening dead air space, as shown in Fig. 6. The reinforcing wire 14, connecting the studs 13, is inclosed in concrete, as shown in Fig. 4, the concrete being interposed 20 between the studs 13 to strengthen the skeleton frame 15. Anchors 14' are embedded at their lower ends in the concrete and fastened at their upper ends to the studs and thus reinforce the studs from the base. 25 These anchors are preferably provided with cross heads, at their lower ends to firmly fix them in the base. Reinforcing rings or bands 13' are also preferably employed to strengthen the skeleton frame 15.

30 It will now be seen that by providing a silo of the character described, a structure is presented which will not only efficiently resist the wear of the elements and the usual wear and tear to which silos are usually subjected, but the same will also provide a receptacle for conveniently containing the ensilage and which can be readily removed from the silo through the openings provided by the closures 34, which are independently 35 removable, as mentioned heretofore.

A follower 37 is provided, as shown in Figs. 2, 9 and 10, the said follower being adapted to be placed in the silo after the same has been filled with ensilage and adapted 40 to act as a cover for the ensilage, thus also applying a downward pressure to the ensilage for firmly packing the same in the silo. The follower consists more substantially of a series of segmental sections 38, 45 each section being formed of a band-like frame 39 inclosing a segmental body 40 consisting preferably of a layer of plaster or concrete 41, a layer of reinforcing wire 42 and several layers of paper 43 having plaster 50 44 or some other similar material interposed therebetween, as shown in Fig. 10. When each of the bodies 40 are arranged so that their apices terminate at a common center, as shown in Fig. 9, the assembled follower 55 will be circular in shape so that the same will snugly fit within the receptacle 12, each of the bodies 40 being connected to the adjacent bodies by rings 45 encircling the longer portions of the frames 39 of the sections 38. Referring to Fig. 1 it will be seen

that the reinforcing wire beneath the outer wall of plaster can preferably include a wire of fine mesh overlying a wire of coarser mesh with the wires forming the coarser mesh arranged in diagonal relation, as 70 shown, it being understood, however, that the wire including the fine and coarse mesh can be made as in one piece rather than separately as shown in Fig. 1. After the follower 37 has been placed within the receptacle 12 to repose upon the ensilage therein, a series of strips 46 are preferably 75 arranged upon the upper face of the follower to cover the spaces between the adjacent sections 38, as shown in Fig. 2, the said strips being arranged to radiate from the center of the follower and terminate at the periphery of the follower.

By constructing the silo described of metal and plaster or concrete the deficiencies of wooden built silos are overcome, it being well known that silos built of wood quickly warp, thus greatly weakening the structure. It will be further noted by referring to Fig. 2 that dead air spaces are provided between the inner and outer walls of the silo, the said spaces being formed between the spaced studs of the skeleton frame 15 and by forming the silo with inner and outer spaced walls a structure is presented that will 90 neither warp nor rot, the metallic reinforcing employed in constructing the walls of the silo being protected from the elements by the plaster overlying the same.

Having thus described the invention what 100 is claimed as new, is:

1. In a silo the combination with a base, of a receptacle supported thereon and including a skeleton frame, studs forming a part of the skeleton frame and embedded in the said base, the said studs being relatively spaced apart, inner and outer walls consisting of sheathing, reinforcing members and plaster, the said walls being supported on the said studs with the studs interposed therebetween to form air spaces, uprights formed between the said studs and extending vertically beyond the upper edge of the said receptacle, and a supporting frame supported on the said uprights.

2. In a silo the combination with a base, of a receptacle supported thereby and consisting of a skeleton frame rigid with the base and including spaced studs, reinforcing means connecting the said studs, inner and outer walls having the said studs interposed therebetween to space the walls, uprights formed between the said studs and projecting beyond the upper edge of the receptacle, reinforcing rods embedded in the said uprights and extending longitudinally therein and a supporting frame supported on the upper ends of the said uprights.

3. In a silo the combination with a base, of a receptacle supported thereby and con-

sisting of a skeleton frame rigid with the base and including spaced studs, reinforcing means connecting the said studs, inner and outer walls having the said studs interposed therebetween to space the walls, uprights formed between the said studs and projecting beyond the upper edge of the receptacle, and a supporting frame supported on the upper ends of the said uprights.

4. A silo comprising a base, and a silo body supported thereby, said body consisting of a skeleton frame rigid with the base and including spaced studs embedded at their lower ends in said base, spaced inner and outer walls secured to said studs, uprights formed between certain of said studs and projecting beyond the upper edge of the receptacle, and a supporting frame carried by said uprights.

5. A silo comprising a base, and a silo body supported thereby, said body consisting of a skeleton frame including studs em-

bedded in and rising from the base, spaced inner and outer walls secured to said studs, 25 concrete uprights formed between certain of said studs and projecting beyond the upper edge of the receptacle, longitudinal reinforcing elements embedded in said uprights, and a supporting frame mounted 30 upon the upper ends of said uprights.

6. In a silo, the combination with a concrete base, of a receptacle formed of inner and outer walls and studs, the said studs extending into the said base, anchors embedded in the base and rising therefrom to engage the studs, and reinforcing means connecting the said studs and passing through the upper ends of the said anchors.

In testimony whereof I affix my signature in presence of two witnesses.

FRANKLIN P. VAN HOOK.
